(57) **CLAIM**

The ornamental design for a self-bailing boat, as shown and described.

DESCRIPTION

FIG. 1 is a right perspective view of a self-bailing boat showing my new design;

FIG. 2 is a left perspective view thereof;

FIG. 3 is an enlarged front perspective view thereof;

FIG. 4 is an enlarged rear perspective view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the self-bailing boat that form no part of the claimed design.
